UNITED STATES PATENT OFFICE

2,426,763

CURVED HANDLE WRENCH FOR RELATIVELY INACCESSIBLE THREADED OBJECTS

Earl M. Curtis, Paw Paw, Mich.

Application October 6, 1943, Serial No. 505,183

2 Claims. (Cl. 81—119)

1

This invention relates to improvements in curved handle wrench for relatively inaccessible threaded objects.

The main objects of this invention are:

First, to provide a wrench which is well adapted and effective for use in the manipulation of bolts or threaded members in relatively inaccessible positions such, for example, as between crankshaft bearings and flywheels or clutch members or the like.

Second, to provide a wrench which greatly facilitates the assembling and disassembling of parts particularly in motor vehicles where the bolts or nuts are closely adjacent to other parts.

Objects relating to details and economies of the invention will appear from the description to follow. The invention is defined and pointed out in the claims.

A preferred embodiment of the invention is illustrated in the accompanying drawing, in which:

Fig. 1 is a side elevation of my improved wrench.

Fig. 2 is a fragmentary elevation illustrating the operation of the wrench by full and dotted lines, the view being partially in section on line 2—2 of Fig. 3.

Fig. 3 is a fragmentary longitudinal section on line 3—3 of Fig. 2.

In the accompanying drawing, I illustrate the crankshaft of an internal combustion engine 1, its bearing 2, flywheel 3, and the packing designated generally by the numeral 4 for the purpose of illustrating one use of my improved wrench. A packing assembly is secured by means of the lag screws 5.

It will be noted that the space between the end of the bearing and crankshaft flange 6 and flywheel 3 is very restricted and these are usually positioned in a motor vehicle where the accessibility is further restricted by body and chassis elements and commonly a relatively large amount of time is required in assembling and replacing these parts and similar parts and the work is arduous and requires considerable skill.

My improved wrench comprises an elongated S-shaped handle 7 having a wrench member 8 pivoted to one end and a wrench member 9 pivotally connected to the other end. These wrench members have relatively short shanks as is clearly shown in the drawing. The pivots 10 are set up to the point where they provide means for frictionally holding the wrench members in their adjusted positions.

Spring washers 11 are arranged between the

handle and the wrench or jaw members, these being preferably dished spring washers which secure the desired friction. This provides means for holding the wrench or jaw members in their adjusted positions for conveniently engaging with the work in various positions and at the same time permits the actuation of the wrench or jaw members by a longitudinal reciprocating movement of the handle. The rivets which constitute the pivots may be set up to secure the desired friction without the use of spring washers or a friction disk may be interposed between the shanks of the jaw members and the handle but the spring washer is preferred.

15 The wrench or jaw member 8 is of the open jaw type opening radially outwardly from the pivot 10 of the jaw member and adapted to be slipped laterally upon the head of a bolt or upon a nut or adapted to be engageable over the work by movement of the jaw member in a direction radially thereof. The jaw member 9 is of the socket type having a closed work receiving jaw 12 with a plurality of internal work engaging teeth 13. The curved offset end portion at each 20 end of the handle provided by the S-shape of the same permits each jaw member to be adjusted to an operative position substantially laterally offset from an end portion and to extend substantially parallel to the general direction of the handle, as is shown substantially in Fig. 2.

With my improved wrench, the placing and removing of lag screws, nuts and the like in relatively inaccessible positions is greatly expedited and the work is greatly expedited as well as lessening the strain and fatigue on the operator.

30 By making the handle of S-shape, it is easy to grasp and manipulate when using either jaw member and by making it thin it can be worked and manipulated in confined or restricted spaces and constitutes a minimum of obstruction to the vision of the user. It should be noted that the jaw of the jaw member 8 opening radially outwardly away from the pivot 10 of the jaw member permits the jaw to be engaged over the head of an upper lag screw 5 by a thrust in a direction more or less longitudinally of the jaw member and directly against the pivot. This greatly facilitates engagement of the jaw with the head of said upper lag screw, since it minimizes tendency of the jaw member to turn in effecting such engagement. Also the jaw member 8 is pivotally adjustable on the handle 7 to a position that permits the open end of the jaw to engage the head of the upper lag screw 5 by a thrust in a direction substantially longitudinally of said handle

and away from said jaw member. This in combination with the curved end of the handle to which the relatively short jaw member 8 is pivoted facilitates engagement of the jaw with the head of the upper lag screw 5 and the turning thereof. The handle 10 may be operated substantially vertically to effect such operations and requires relatively little space.

I have illustrated a very practical embodiment of my invention. I have not attempted to illustrate certain modifications in the matter of design as it is believed that this disclosure will enable those skilled in the art to embody or adapt my invention as may be desired.

Having thus described my invention, what I claim as new and desire to secure by Letters Patent, is:

1. In a wrench, the combination of a relatively long handle having a curved offset end portion, of a jaw member having a relatively short shank pivoted to the outer end of said curved offset end portion, the pivot being transverse to the plane of the curved offset end portion and transverse to the jaw member and frictionally holding the jaw member in different positions of adjustment on that side of the handle as is located the curved offset end portion, said jaw member being of the open jaw type opening radially outward from the pivot of said jaw member to permit the jaw member to be engaged with the work by a thrust of the jaw member in a direction longitudinally thereof and towards said pivot, said jaw member being pivotally adjustable on said handle to a position that permits the open end of the jaw to engage the work by a thrust in a direction substantially longitudinally of the handle and away from said jaw member, said curved offset end portion being of a curvature and dimensions to permit said jaw member for substantially the entire length thereof to be pivotally adjusted to an operative position substantially laterally offset from said end portion when the jaw member extends substantially parallel to the general direction of the handle.

2. In a wrench, the combination with a relatively long substantially S-shaped handle, of a jaw member having a relatively short shank pivoted to one end of said handle to swing substantially in the plane of the curved end to which it is pivoted and on the inner curved side of said end, and a friction element associated with the pivot, handle and jaw member for frictionally holding the jaw member in different positions of adjustment for engagement with the work, said shank having a jaw at the outer end thereof, said jaw being of the open jaw type and opening radially outwardly away from the pivot of said shank to permit the jaw to be engaged with the work by a thrust on the jaw member in a direction substantially towards said pivot, said jaw member being pivotally adjustable on said handle to a position that permits the open end of said jaw to engage the work by a thrust in a direction substantially longitudinally of the handle and away from said jaw member, the curved end portion of the handle to which said jaw member is pivoted being of a curvature and dimensions to permit substantially the entire length of said jaw member being substantially spaced from said curved end portion when the jaw member extends substantially parallel to the general direction of the handle.
